UNITED STATES PATENT OFFICE

JOHN T. OVERSTREET, OF SAN ANTONIO, TEXAS

WELL PUMPING APPARATUS

Application filed November 19, 1926, Serial No. 149,430. Renewed May 13, 1930.

My invention relates to an apparatus for use in wells for elevating oil, water, or the like, from the bottom of a well to the surface of the ground, and aims to provide a novel and improved device of this character which may be conveniently arranged in a well for efficiently elevating oil or water therefrom.

The invention contemplates the provision of an inlet pipe leading down into the well from the surface of the ground and opening into a suction or vacuum chamber having an inlet valve leading therein for permitting the entrance of oil or water from the well into the chamber, said inlet pipe opening into the suction or vacuum chamber in alignment with a passageway in communication with an outlet pipe leading to the surface of the ground, so that upon the forcing of water or other liquid down the inlet pipe into the passageway a suction will be created in the suction or vacuum chamber which causes the water or oil in the well to enter the suction or vacuum chamber through the valve and be carried to the surface of the ground with the first mentioned liquid under pressure.

It is also an object of the invention to provide an apparatus of the above indicated character, which is simple and substantial in construction, which can be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a longitudinal section through my improved apparatus, showing the upper ends of the inlet and outlet pipes broken away,

Figure 2 is a cross section taken on line 2—2 of Figure 1,

Figure 3 is a fragmentary sectional view of a modification of the means of communica-

tion of the inlet pipe with the outlet pipe in the suction or vacuum chamber, and

Figure 4 is another fragmentary section showing a still further modified form, in which the distance between the inlet passageway and the outlet passageway may be adjusted for causing greater or less suction or vacuum in the suction chamber.

Referring to the drawings, the numeral 10 designates a relatively large casing extending into a well from the surface of the ground to a point below the level of liquid in the well. On the lower end of the casing 10 is threaded, as at 11, a main body 12. The main body 12 has arranged therein and spaced from the walls thereof a vacuum or suction chamber 13, opening out at one side of the body 12, as at 14, said chamber being cylindrical in shape and provided at its inner end with a cylindrical depending portion or outlet 15. Rising from the upper wall of the suction chamber above the depending portion or outlet 15 is a collar 16 into which is threaded the lower end of an inlet tube 17 extending to the surface of the ground and is arranged in the casing 10 adjacent one side thereof.

Depending from the upper wall of the vacuum or suction chamber centrally of the depending portion 15 and on a line with the center of the collar 16 is a restricted depending sleeve 18, on the lower end of which is threaded a nozzle 19, the opening through which is tapered and restricted, as at 20. Threaded into the upper end of the depending sleeve 18 at the center of collar 16 is a tubular member 21 which extends upwardly into the tube 17 and has its upper end closed, as at 22. This tubular member is of a great deal less size than the tube 17 so that a space is formed around the same for catching and holding scale, thus forming a scale trap, as indicated by the numeral 23, and in the upper part of its cylindrical wall is a series of openings 24 for permitting the entrance of liquid from the tube 17 into the tubular member 21. As the openings 24 are arranged above the lower portion of the tubular member 21, it can thus be seen that scale collected around

the tubular member will not enter said openings.

The depending portion or outlet 15 of the vacuum or suction chamber is threaded to receive the upper end of a tubular member 26 the opening through which forms a jet race, enlarged at the upper end, as at 27, to gradually merge into the outlet of the suction or vacuum chamber. The member 26 is in alignment with the nozzle 19 on the depending sleeve 18 so that liquid forced through said nozzle will be directed into the passageway or jet race. On the lower end of the main body 12 is threaded or otherwise secured an enlarged cup-shaped bowl 28 at which the member 26 slightly protrudes, said cup-shaped bowl being in communication with the main opening through the body 12 and the main casing 10. The vacuum or suction chamber 13 is internally screw threaded, as at 29, adjacent the point where it opens exteriorly of the body 12 to receive a flanged collar 30 having an inclined valve seat 31 at its inner end with an inwardly projecting lug 32 at the upper end of said seat and to which is pivoted an arm 33 carrying a flap valve 34, adapted to engage the seat 31 for normally closing the vacuum or suction chamber 13. By inclining the valve seat and pivotally connecting the flapper valve at a point slightly inwardly thereof the weight of the flapper valve will cause the same to normally be in closed position.

For stabilizing the tube 17 within the casing 10 leaf springs 36 bear against the same at suitable intervals throughout the length of said tube, said springs being riveted to the casing as at 35 with their free ends 37 bearing against the tube, and though I have shown but one stabilizing spring, it is to be understood that they are to be provided throughout the entire length of the casing and tube.

In operation of my improved apparatus, a liquid such as water or oil is forced under pressure down the tube 17 from the surface of the ground to the lower end of said tube, and when the liquid reaches the bottom of the tube 17, it will pass through the openings 24 in the sleeve or tubular member 21 and thus be forced through the restricted depending sleeve 18 at a relatively high rate of speed, due to the fact that the opening in the sleeve is a great deal smaller than the opening through the tube 17. The liquid entering the sleeve 18 passes through the nozzle 19 and the speed or velocity thereof is increased to a higher rate and is forced into the jet race or opening through the member 26. As the liquid passes from the nozzle into the jet race, a vacuum or suction is created in the vacuum or suction chamber 13, thus causing the flap valve 34 to open and oil or water, whichever is contained in the well, drawn into the suction or vacuum chamber, from which it will be carried with the liquid forced

down through the tube 17 into the cup-shaped bowl 28, communicating with the casing 10. Thus the liquid forced through the tube 17 and liquid entering through the valve 34 will rise in the casing 10 to the surface of the ground where the same is drawn away. It is to be noted that by arranging the tubular member or sleeve 21 in the tube 17 that all scale or foreign matter contained in the liquid forced down through the tube 17 will collect around the exterior of said member 21 and not enter the interior thereof which would probably cause clogging of the nozzle 19. It is to be noted that the nozzle 19 is arranged at a point in the vacuum or suction chamber where all liquid forced therethrough will be forced directly into the opening or jet race in the member 26, thus preventing such liquid entering the vacuum or suction chamber 13.

In Figure 3 of the drawings, I have shown a modified form of nozzle, wherein I have provided an outwardly flared opening 40 at the discharge end of the nozzle which receives therein a tapered or pointed end 41 of a pin 42 arranged in the member 26, said pin 42 being carried by the lower end of the member 26 by means of webs, or the like, 43. By flaring the discharge opening of the nozzle 19 and arranging a tapered pin in said opening, the liquid forced through the nozzle will be retained at a high rate of speed during its short passage in the vacuum or suction chamber, thus causing a greater vacuum or suction in the chamber for drawing oil or water into the same from the bottom of the well.

In Figure 4 of the drawings, I have shown the sleeve 18 as being exteriorly screw threaded through the upper wall of the vacuum or suction chamber so that the distance or space between the nozzle and the jet race may be adjusted for increasing or decreasing suction in the chamber 13. In this form of my invention, the tubular member 21 is an integral part of the sleeve 18 so that both of said members are moved upon adjustment of the sleeve. While I have shown the sleeve as being threaded for adjustment of the nozzle, it is to be understood that various size nozzles may be used for permitting such adjustment and that a nozzle of greater or less length may be threaded into the sleeve 18 shown in Figure 1 of the drawings for permitting said adjustment.

Having thus described my invention, what I claim as new is:

1. A device of the character described comprising a suction chamber having a depending portion in the bottom thereof of reduced size and an opening in said depending portion, a tube depending from the upper wall of said chamber in line with said opening and terminating at a point adjacent said opening, a tube connected to said depending tubular member for supplying liquid under

high pressure so that it will be forced from the tubular member through the opening, a valve for permitting entrance of liquid in said chamber upon the creation of suction therein, and an outlet pipe in communication with said opening in said chamber.

2. A device of the character described comprising a suction chamber having an outlet opening in the bottom thereof, a tubular member depending from the upper wall of said suction chamber in alignment with said opening and terminating at a point adjacent thereto, a tube connected to said tubular member for supplying liquid under pressure, a sleeve threaded in the tubular member and extending upwardly therefrom into said supply tube so that a trap is arranged around said sleeve for catching scale or the like, a valve for permitting entrance of liquid into the suction chamber from the well when suction is created therein, and an outlet pipe in communication with the outlet opening in said chamber.

3. A device of the character described comprising a suction chamber having an opening therein, a depending tubular member carried by said suction chamber and depending therein in alignment with said opening and terminating at a point adjacent said opening, a tube for supplying liquid under pressure to said tubular member, a sleeve threaded in said tubular member and extending upwardly therefrom into said tube so that a trap is arranged around said sleeve for catching scale or the like, said sleeve having its upper end closed and a series of openings in the cylindrical side walls thereof at a point adjacent its upper end, a valve for permitting entrance of liquid into said chamber upon creating of a suction or vacuum therein, and an outlet pipe in communication with the opening in said chamber.

4. A device of the character described comprising a main body, a suction chamber formed in said main body and spaced from the walls thereof, said suction chamber having an opening in the bottom wall thereof, a tubular member arranged in said chamber in alignment with said opening and terminating at a point adjacent said opening, said tubular member also opening exteriorly of said suction chamber, a tube secured to said body and in communication with said tubular member for supplying a liquid to said tubular member under pressure so that said liquid will be forced through said opening in said suction chamber for creating a suction or vacuum therein, a valve for permitting entrance of liquid in said chamber upon creating of a suction or vacuum therein, a cup-shaped bowl arranged on the lower end of said body, and an outlet casing arranged on the upper end of said body for receiving the liquid after passing through said opening, said casing

and bowl being in communication with each other through said body.

5. A device of the character described comprising a body, a suction chamber arranged in said body, said suction chamber having an opening in the lower wall thereof, a tubular depending member arranged in said suction chamber in alignment with said opening and terminating at a point adjacent said opening, a nozzle arranged upon the lower end of said tubular member, a tube for supplying liquid under pressure to said tubular member, a member secured to said chamber and having a jet race therein so that when liquid under pressure is forced through said nozzle the same will be forced into said jet race thus causing a suction or vacuum in said suction chamber, a valve arranged in said suction chamber for permitting entrance of liquid to said chamber upon creating of a suction or vacuum therein, a bowl arranged on the lower end of said body into which partially extends said member having said jet race, and a casing attached to the upper end of said body and in communication with said bowl.

6. A device of the character described comprising a suction chamber having an opening therein, a depending tubular member carried by said suction chamber in alignment with said opening and terminating at a point adjacent said opening, a tube for supplying liquid to said tubular member under pressure, a nozzle attached to the lower end of said tubular member and having the exit opening thereof flared outwardly, a tapered pin arranged in said flared portion of said nozzle so as to cause liquid forced under pressure from said tube to be forced at a high rate of speed through said opening, a valve for permitting entrance of liquid in said chamber upon suction or vacuum therein, and an outlet pipe in communication with said opening in said chamber.

7. A device of the character described comprising a suction chamber having an opening therein, a depending tubular member carried by said suction chamber in alignment with said opening and terminating at a point adjacent said opening, a tube for supplying liquid to said tubular member under pressure, a nozzle attached to the lower end of said tubular member and having the exit opening thereof flared outwardly, a member secured to said suction chamber and in communication with the opening therein, said member having a jet race therein, a pin carried by said member and having a tapered end thereon adapted to be positioned in said flared end of said nozzle so that liquid forced from said tubular member under pressure will be forced into said jet race at a high rate of speed so as to create a vacuum or suction in said chamber, a valve for permitting entrance of liquid in said chamber upon creating of a suction or vacuum therein, and an outlet

pipe in communication with said opening in said chamber.

8. A jet pump for wells comprising a casing to which the outlet pipe is connected, a suction chamber formed within the casing at one side thereof to leave a space partly surrounding said casing and having an opening leading into the well, a depending outlet in the bottom of the suction chamber at the inner end thereof contracted at its lower end, a jet nozzle depending from the upper wall of the suction chamber on a line with the aforesaid outlet opening, an inlet tube connected to said jet nozzle, and a bowl connected to the lower end of the casing and into which the aforesaid outlet discharges.

9. A jet pump for wells comprising a casing to which the outlet pipe is connected, a suction chamber formed within the casing at one side thereof to leave a space partly surrounding said casing and having an opening leading into the well, a depending outlet in the bottom of the suction chamber at the inner end thereof contracted at its lower end, a jet nozzle depending from the upper wall of the suction chamber on a line with the aforesaid outlet opening, an inlet tube connected to said jet nozzle, and a bowl connected to the lower end of the casing and into which the aforesaid outlet discharges; together with a clap-valve in the inlet opening of the suction chamber.

10. A jet pump for wells comprising a casing to which the outlet pipe is connected, a suction chamber formed within the casing at one side thereof to leave a space partly surrounding said casing and having an opening leading into the well, a depending outlet in the bottom of the suction chamber at the inner end thereof contracted at its lower end, a jet nozzle depending from the upper wall of the suction chamber on a line with the aforesaid outlet opening, an inlet tube connected to said jet nozzle, and a bowl connected to the lower end of the casing and into which the aforesaid outlet discharges; together with a removable collar in the inlet opening of the suction chamber having an inclined valve-seat at its inner end, and a clap valve pivoted above the seat to close against the same.

In testimony whereof, I have affixed my signature.

JOHN T. OVERSTREET.
